1,1,1-TRICHLORO-2,2-BIS[CARBOALKOXY-AMINO]ARYL]ETHANE

Erhard J. Prill, Dayton, Ohio, assignor to Monsanto Chemical Company, St. Louis, Mo., a corporation of Delaware
No Drawing. Filed Feb. 12, 1960, Ser. No. 8,246
4 Claims. (Cl. 260—471)

The present invention relates to organic nitrogen compounds and more particularly provides a new and valuable series of chlorinated nitrogenous esters and the method of preparing the same.

According to the invention, there are provided certain 1,1,1-trichloro-2,2-bis(carboalkoxyaminoaryl)ethanes by the reaction of chloral with an alkyl ester of an N-aryl carbamic acid, substantially according to the scheme:

wherein Ar denotes an aromatic hydrocarbon radical of from 6 to 12 carbon atoms which is attached to the remainder of the molecule of which it forms a part through a ring carbon atom thereof, and Alk denotes an alkyl radical of from 1 to 5 carbon atoms.

Presently useful alkyl esters include those of carbanilic acid, i.e., compounds of the formula

in which Alk is as above defined, R is selected from the class consisting of hydrogen and alkyl radicals of from 1 to 6 carbon atoms, n is an integer of from 1 to 4, and the total number of carbon atoms in the total number of R radicals is from 1 to 6. Examples thereof are the ethyl, methyl, n-propyl, isopropyl, n-butyl, tert-butyl, n-amyl and tert-amyl carbanilates. Derivatives of said alkyl carbanilates wherein there is present one or more lower alkyl substituents are likewise useful. Thus, there may be employed the methyl, ethyl, propyl, butyl or amyl esters of such ar-alkylcarbanilic acids as the 2-, 3-, or 4-methylcarbanilic acid, 2-, 3-, or 4-ethylcarbanilic acid, 2-, 3-, or 4-n-propylcarbanilic acid, 2-, 3-, or 4-tert-butylcarbanilic acid, 2-, 3-, or 4-isoamylcarbanilic acid, or 2-, 3- or 4-hexylcarbanilic acid. Also useful are the alkyl esters of di- or poly-alkylated carbanilic acids such as 3,4- or 2,3-dipropyl carbanilic acid, the 2,3,5-trimethylcarbanilic acid, or tetramethylcarbanilic acid. Likewise useful are the alkyl phenylcarbanilates, i.e., the alkyl N-xenylcarbamates of the structure

wherein Alk is as herein defined, and the alkyl N-naphthylcarbamates of the structure

where Alk is as herein defined, Y is selected from the class consisting of hydrogen and alkyl radicals of from 1 to 2 carbon atoms, x is a number of from 1 to 2, and the total number of carbon atoms in the total Y radicals is 2.

The following compounds are provided by the present

2

invention wherein chloral is reacted with the appropriate N-aryl carbamate:

- 1,1,1-trichloro-2,2-bis[4-(carbomethoxyamino)phenyl]-ethane
- 1,1,1-trichloro-2,2-bis[2-(carboethoxyamino)phenyl]-ethane
- 1,1,1-trichloro-2,2-bis[2-(carboisopropoxyamino)phenyl]ethane
- 1,1,1-trichloro-2,2-bis[4-(carbo-n-butoxyamino)phenyl]ethane
- 1,1,1-trichloro-2,2-bis[4-ethyl-2-(carbomethoxyamino)phenyl]ethane
- 1,1,1-trichloro-2,2-bis[4-(carbomethoxyamino)-2,3-dimethylphenyl]ethane
- 1,1,1-trichloro-2,2-bis[2-n-propyl-4-(carbomethoxyamino)phenyl]ethane
- 1,1,1-trichloro-2,2-bis[4-phenyl-2-(carbobutoxyamino)phenyl]ethane
- 1,1,1-trichloro-2,2-bis[2,3,5-trimethyl-4-(carboamyoxyamino)-phenyl]ethane
- 1,1,1-trichloro-2,2-bis[2-amyl-3-butyl-4-(carboethoxyamino)phenyl]ethane
- 1,1,1-trichloro-2,2-bis[diisopropyl(carboethoxyamino)phenyl]ethane
- 1,1,1-trichloro-2,2-bis[2,3,4,5-tetramethyl-6-(carbomethoxyamino)phenyl]ethane
- 1,1,1-trichloro-2,2-bis[2-(carboethoxyamino)-1-naphthyl]ethane
- 1,1,1-trichloro-2,2-bis[1-(carbopropoxyamino)-7-ethyl-2-naphthyl]ethane

Reaction of the chloral with the arylcarbamate occurs at the aromatic nucleus. Thus with a methyl ethylcarbamate the reaction proceeds as follows:

Condensation of the chloral with the carbamate occurs by simply mixing the two reactants, advantageously in the presence of catalyst or condensing agent, and allowing the mixture to stand until formation of the 1,1,1-trichloro-2,2-bis(carboalkoxyaminobenzoid)ethane has occurred. Since the reaction is exothermic, generally no external heating is required. However, when working with large quantities, external cooling may be needed. Depending upon the nature of the individual N-aryl carbamate, a solvent or diluent may or may not be employed. Useful solvents are, e.g., aliphatic or aromatic hydrocarbons such as hexane, benzene or xylene; chlorinated hydrocarbons such as carbon tetrachloride or dichlorobenzene; ether such as ethyl ether or dioxane, etc. Since the reaction takes place by condensation of one mole of the chloral with two moles of the N-benzenoid carbamate, these reactants are advantageously employed in such stoichiometric proportions; however, an excess of either reactant may be employed since any unreacted reagent is readily recovered from the final reaction product.

While the condensation takes place in the presence or absence of a catalyst, it is generally advantageous to employ an organic or inorganic acidic material as catalyst. Examples of presently useful catalysts are sulfuric acid,

4-toluenesulfonic acid, glacial acetic acid, acidic salts such as ferric chloride or boron trichloride, etc. Compounds of the Lewis acid type are generally useful. Although the reaction takes place readily at atmospheric pressure, it may be effected at either super-atmospheric or sub-atmospheric pressures. Thorough stirring of the reaction mixture is recommended for dissipation of the heat evolved in the exothermic reaction.

The presently provided 1,1,1-trichloro-2,2-bis[carboalkoxyamino]arylethanes are generally stable, high-melting solids or high-boiling viscous liquids which are advantageously employed for a variety of commercial and biological purposes, e.g., as lubricant additives, plasticizers for synthetic resins and plastics, rubber-compounding constituents, etc. When used as plasticizers, they also impart flame-proofing effect. The presently provided compounds are likewise useful as insecticides, fungicides and bacteriostats.

The invention is further illustrated, but not limited, by the following examples:

Example 1

Molten methyl carbanilate (151 g., 1 mole) was added to concentrated sulfuric acid (300 ml.) at 5-10° C. with stirring. Chloral (73.5 g., 0.54 mole) was added in 5 minutes. No heat effect was noticeable. Stirring was continued without cooling and a slow reaction took the pot temperature from 12° C. to 43° C. in one hour. After an additional two hours the temperature had dropped to 35° C. The contents of the flask was poured over ice. The white solid which precipitated was removed by filtration and was washed well with water including one re-slurry. After air-drying for two days the product, 174 g. (87% yield), melted at 196-8° C. with decomposition. Two recrystallizations from acetone-methanol gave white crystals of the substantially pure 1,1,1-trichloro-2,2-bis[4-carbomethoxyamino]phenylethane, melting at 207-9° C., and analyzing as follows:

	Found	Calcd. for C ₁₈ H ₁₇ Cl ₃ N ₂ O ₄
Percent C.....	50.29	50.2
Percent H.....	4.22	3.95

The 1,1,1-trichloro-2,2-bis[4-carbomethoxyamino]phenylethane was converted to the prior art 1,1-dichloro-2,2-bis[4-carbomethoxyamino]phenylethylene, M.P. 212.5-214° C., by refluxing with potassium hydroxide in methanol. The structure of the presently provided 1,1,1-trichloro-2,2-bis[4-carbomethoxyamino]phenylethane was thereby substantiated.

Operating as above, other alkyl carbanilates having from 1 to 5 carbon atoms in the alkyl radical are similarly converted to 1,1,1-trichloro-2,2-bis[carboalkoxyamino]phenylethanes; thus, instead of the methyl carbanilate used above, there may be employed either ethyl, butyl, or amyl carbanilate or alkyl carbanilates carrying on the benzene ring thereof one or more lower alkyl substituents, e.g., methyl 4-ethyl carbanilate or amyl 2,3-dimethyl carbanilate. Thus, reaction of chloral with amyl 2-hexylcarbanilate using the procedure described above gives the 1,1,1-trichloro-2,2-bis[2-hexyl-4-(carboamyl-oxy)phenylethane].

Example 2

To a four-necked, 500 ml. flask fitted with mechanical stirrer, reflux condenser, thermometer and dropping funnel there was charged 94 g. (0.438 mole) of ethyl N-(2-naphthyl)carbamate. To this there was added, while cooling in the ice-bath, 150 ml. of concentrated sulfuric acid. The temperature of the resulting mixture was brought to 10° C., and there was gradually added thereto, during a 15-minute period, 33 g. of freshly distilled chloral. When all of the chloral had been added and ice-cooling was discontinued, the temperature of the reaction

mixture rose spontaneously to 37° C. The mixture was then warmed at 43°-45° C. for 3 hours. The resulting dark green reaction mixture was then allowed to stand overnight at room temperature. At the end of that time it had turned to a clear, dark brown solution. It was poured on ice, with stirring, and allowed to stand for separation of solids. After decanting the resulting aqueous layer, the solids were stirred in the Waring Blender, and the milky upper layer was discarded. The residual solids were re-washed, first with water, then with ammoniacal water and finally with water. Upon oven-drying of the washed material there was obtained the powderlike 1,1,1-trichloro-2,2-bis[1-(carboethoxyamino)-2-naphthyl]ethane, analyzing 5.02% nitrogen as against 5.0%, the calculated value for C₂₈H₂₅N₂O₄Cl₃. It was partly soluble in toluene, ethanol or ether and completely soluble in acetone.

The 1,1,1-trichloro-2,2-bis[carboalkoxyamino]arylethanes possess bacteriostat effect at very low concentrations. Thus, in vitro tests of the 1,1,1-trichloro-2,2-bis[4-carbomethoxyamino]phenylethane of Example 1 showed inhibition of *Mycobacterium tuberculosis* at a concentration of 0.2 mg./cc. When used as bacteriostats, the present compounds are advantageously incorporated into organic solvents, say ethanol or isopropanol, or they may also be admixed with soaps or synthetic detergents. As fungicides, the present compounds are highly efficient for preventing and retarding fungus growth on textiles, fur, leather, woods, etc. For either fungicidal or insecticidal use the 1,1,1-trichloro-2,2-bis[carboalkoxyamino]arylethanes are generally applied in the form of sprays or aerosols. Sprays may be prepared by dissolving the presently provided compounds in the usual organic solvents, e.g., acetone, hexane, benzene, carbon tetrachloride, kerosene, etc.; but it is preferred to prepare the sprays by incorporating the present reaction products into aqueous emulsions because less of the active ingredients, i.e., 1,1,1-trichloro-2,2-bis[carboalkoxyamino]arylethanes, is thus required to give comparable insecticidal efficiency. The emulsions are readily made by adding to one of the present compounds an emulsifying agent, if desired, first dissolving or suspending said compound in an organic solvent immiscible with water, i.e., an "oil," before the addition of the emulsifying agent, and then mixing with water to form an emulsion. Because of the very high biological efficiency of the present reaction products, they need be present in the emulsion in only very small concentrations, for example, in concentrations of 100 to 10,000 parts per million by weight of the total emulsion. Emulsifying agents which may be employed are those customarily used in the art for the preparation of oil-in-water emulsions, e.g., long-chained polyalkylene glycols, long-chained alkyl sulfosuccinates, etc.

The present compounds may also be dissolved in liquefied gases such as the fluorochloroethanes or methyl chloride and applied from aerosol bombs containing the solution.

Instead of employing liquids as carriers and diluents, pesticidal dusts comprising the present compounds may be prepared by grinding or milling the reaction products prepared in accordance with this invention with a pulverulent carrier. Kaolin, bentonite, chalk, talc, etc. can be used as carriers. Wetting and adhesive agents may, if desired, be used as additives, for example, in a composition comprising eighty parts of inert carrier, ten parts of active ingredient (the reaction product of the invention) and ten parts of adhesive or wetting agent additive. Such a wettable powder may be further diluted with inert carrier to produce emulsions containing the powder in a concentration of from 0.1 to one percent.

The present compounds or compositions containing the same may usefully be applied directly to insects or fungi or they may be applied to the fruit or foliage of plants or other potential hosts in advance of the anticipated in-

festation. The term "insect" is herein used to include mites and allied classes of arthropods such as spiders, centipedes, etc., as well as true Hexapoda, i.e., six-legged invertebrates.

While the invention has been described with particular reference to various preferred embodiments thereof, it will be appreciated that numerous modifications and variations are possible without departure from the invention and the invention is not to be limited to any specific embodiment thereof except as defined in the appended claims.

This application is a continuation-in-part of my application Serial No. 700,960, filed December 6, 1957, and now abandoned.

What I claim is:

1. An ester having the formula

wherein Ar is selected from the class consisting of phenyl, alkyl-substituted phenyl having from 7 to 12 carbon atoms, biphenyllyl, naphthyl and alkyl-substituted naphthyl hav-

15

20

ing a total of from 11 to 12 carbon atoms, and is attached to the remainder of the molecule of which it forms a part through a ring carbon atom thereof, and Alk denotes alkyl of from 1 to 5 carbon atoms.

5 2. A 1,1,1-trichloro-2,2-bis[(carboalkoxyamino)phenyl]ethane having from 1 to 5 carbon atoms in the alkoxy.

3. 1,1,1-trichloro-2,2-bis[4-(carbomethoxyamino)phenyl]ethane.

10 4. 1,1,1-trichloro-2,2-bis[(carboethoxyamino)-2-naphthyl]ethane.
